CLAIM

The ornamental design for a video conference terminal as shown and described.

DESCRIPTION

FIG. 1 is a front perspective view of a video conference terminal showing our new design;

FIG. 2 is a front view thereof;

FIG. 3 is a cross-sectional view taken through line 3-3 of FIG. 2; and,

FIG. 4 is an enlarged view of the encircled portion 4 indicated in FIG. 1.

The broken lines depict portions of the video conference terminal that form no part of the claimed design. The dot-dash broken lines encircling an enlargement portion of the design forms no part of the claimed design.
